UNITED STATES PATENT OFFICE.

KARL KELLER, OF ARBON, SWITZERLAND, ASSIGNOR TO THE FIRM OF ADOLPH SAURER, OF ARBON, SWITZERLAND.

EMBROIDERING-MACHINE.

1,073,765.

Specification of Letters Patent. Patented Sept. 23, 1913.

Application filed June 11, 1912. Serial No. 703,036.

To all whom it may concern:

Be it known that I, KARL KELLER, a citizen of the Republic of Switzerland, residing at Romanshornerstrasse, Arbon, Switzerland, 5 have invented certain new and useful Improvements in Embroidering-Machines; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 My invention relates to a mechanism for impelling the shuttles and needles of embroidery machines by means of two cams mounted on the driving shaft.

According to my invention a bell-crank 20 lever mounted to rock about a fixed axle and attached to a connecting rod is positively rocked in such manner, that the motion in one direction is produced by the action of one of the cams on one arm of 25 the bell-crank lever and the motion in the opposite direction by the action of the second cam on the second arm of the bell-crank lever. Two such bell-crank levers are provided for impelling a connecting link which 30 itself is used to vary the stitch in a well-known manner.

As compared with the mechanisms which hitherto have been proposed for this purpose, the mechanism according to this invention possesses the advantage, that the regulation of the movements of the needles and shuttles becomes very easy while hitherto the regulation could be performed only by very complicated means. Moreover by 35 the use of the connecting-link a very perfect variation of the stitch is obtained.

The accompanying drawings illustrate the invention by way of example.

Figure 1 is a vertical section. Fig. 2 a 40 horizontal section and Fig. 3 a front view of the same. Fig. 4 is a plan view showing parts of Fig. 1.

Two pairs of cams 3, 4, 5, 6 are mounted on the driving shaft 1, the pairs of cams 50 being of different curvature. Two pairs of crank-levers 7, 8 and 9, 10 are mounted on the frame 2 of the embroidery machine and provided with rolls 11, 12, 13, and 14, which engage the periphery of the cams. A 55 crank-lever and a pair of cams are omitted

in Fig. 1 for the sake of clearness. Connecting rods 15 and 16 attached to the arms 7 and 10 of the crank-levers carry at one extremity, opposite to the rolls, a connecting link 17 of segment form, in which a slide 60 block 18 is fitted. By means of an axle 31, passing through the block 18 the drawing rods 15, 16 are connected with one arm of a bell-crank lever 32, whose other arm engages in the drawing rod 33. Several of these 65 drawing rods are provided, of which only one is shown on the drawing. The drawing rods are guided in a straight line and engage in the shuttle guide holder bar 34. 35 designates the shuttles and 36 the shuttle slide 70 tracks. The needles are impelled from the bell-crank lever 32 in a well-known manner.

Above the bell-crank levers 7, 8 and 9, 10 an axle 19 is secured to the frame 2 of the embroidery machine, about which axle a 75 lever 20 is mounted to rock. A rod 21 composed of two parts is pivoted by one end to the lever 20 and by the other end to the connecting rod 15. Those ends of the parts of rod 21 which are turned toward each 80 other are provided with right- and left-handed threads and connected to each other by a nut 22 provided with corresponding threads. By this means the length of rod 21 can be adjusted. The connecting link 17 85 may be secured at any desired level by securing the lever 20 in a distinct position. For this purpose a bolt 23 is guided in openings provided in projections of the lever 20. The bolt is pressed by a spring 24 into the 90 recesses of a toothed segment 25. In order to release the lever 20 the bolt may be drawn back by means of the handle 23^a in which position it can be secured by a projection 20^b of the lever. A toothed wheel 26 95 mounted on the driving shaft 1 meshes with a toothed wheel 26^a of larger diameter mounted on the shaft 27. The latter shaft carries a disk 28. An arm 29 mounted to rock about the axle 19 carries a roller 29^a 100 which projects into the lateral cam groove 28^a of the disk 28. The arm 29 can be connected to the lever 20 by moving a slide 30 attached to the arm 29 into a forked projection 20^c of the lever 20.

By revolving the driving shaft 1 the connecting rods 15, 16 and the connecting link 17 are reciprocated by the cams 3, 4, 5 and 6. If the connecting link is in the position shown in full lines in Fig. 1 back-stitch 110

is produced, while if the connecting link is raised into the position shown in dotted lines running stitch is produced. The change may be performed either by hand or 5 automatically. In the first case the lever 20 and the arm 29 are disconnected whereafter the lever 20 and the connecting link 17 may be secured in the desired position by means of the bolt 23 and the toothed segment 25. 10 If however the change is to be performed automatically the bolt 23 is released from the toothed segment 25 but the lever 20 is connected to the arm 29 by means of the slide 30. The shaft 27 is then revolved from 15 the driving shaft by means of the toothed wheels, whereby the arm 29, lever 20 and connecting link 17 are vertically reciprocated. Any desired ratio of gearing of the shafts 1 and 27 may be selected by 20 correspondingly selecting the toothed wheels. If for instance the shaft 27 performs one revolution during three revolutions of shaft 1, there are always produced two back-strokes and thereafter one running stitch. By 25 changing the ratio of gearing the ratio of the stitches may be changed. By lengthening or shortening the rod 21 the degree of the stitch can be changed and any variety between the two extremes may be obtained.

30 I claim:

1. In a mechanism for impelling the shuttles and needles of embroidering machines, the combination with a stitching mechanism, of a driving shaft, two cams thereon, 35 a bell-crank lever, a slotted member, means connecting the bell-crank lever to the latter and a slide in the slot connected to the stitching mechanism, the bell-crank lever being positively rocked by said cams so that 40 the motion in one direction is produced by the action of one of the cams on one arm of the bell-crank lever and the motion in the opposite direction by the action of the second cam on the second arm of the bell- 45 crank lever.

2. In a mechanism for impelling the shuttles and needles of embroidering machines, the combination with a stitching mechanism, of a driving shaft, two pairs of cams 50 of different curvature on said shaft, a connecting link, a slide in the connecting link connected to the stitching mechanism, and two connecting rods each being positively reciprocated by one pair of said cams, each 55 end of said connecting link being attached to one of said connecting rods.

3. In a mechanism for impelling the shuttles and needles of embroidering machines, the combination with a stitching mechanism, of a driving shaft, two pairs of cams 60 of different curvature on said shaft, a connecting link, a slide in the connecting link connected to the stitching mechanism, two bell-crank levers, each being moved in one 65 direction by the action of one of said cams

on one of its arms and in the opposite direction by the action of a second cam on the second arm of said lever, and two connecting rods, each end of the connecting link being attached to one of the bell-crank 70 levers.

4. In a mechanism for impelling the shuttles and needles of embroidering machines, the combination with a stitching mechanism, of a driving shaft, two pairs of cams 75 of different curvature on said shaft, a connecting link, a slide in the connecting link connected to the stitching mechanism, two connecting rods each being positively reciprocated by one pair of said cams and each 80 end of said connecting link being attached to one of said connecting rods, and means for regulating the position of the connecting link so that its movements depend more on the one or the other connecting rod. 85

5. In a mechanism for impelling the shuttles and needles of embroidering machines, the combination with a stitching mechanism, of a driving shaft, two pairs of cams 90 of different curvature on said shaft, a connecting link, a slide in the connecting link connected to the stitching mechanism, two connecting rods each being positively reciprocated by one pair of said cams, each end 95 of said connecting link being attached to one of said connecting rods, and means for automatically regulating the position of the connecting link so that its movements depend more on the one or the other connecting rod. 100

6. In a mechanism for impelling the shuttles and needles of embroidering machines, the combination with a stitching mechanism, of a driving shaft, two pairs of cams 105 of different curvature on said shaft, a connecting link, a slide in the connecting link connected to the stitching mechanism, two connecting rods each being reciprocated by one pair of said cams and each end of said 110 connecting link being attached to one of said connecting rods, and means for regulating the position of the connecting link. 115

7. In a mechanism for impelling the shuttles and needles of embroidering machines, the combination with a stitching mechanism, of a driving shaft, two pairs of cams 120 of different curvature on said shaft, a connecting link, a slide in the connecting link connected to the stitching mechanism, two connecting rods positively reciprocated by 125 said pairs of cams, each end of said connecting link being attached to one of said connecting rods, means for regulating the position of the connecting link so that its movements depend more on the one or the other connecting rod, and means for securing the connecting link in position.

8. In a mechanism for impelling the shuttles and needles of embroidering machines, the combination with a stitching mecha- 130

nism, of a driving shaft, two pairs of cams of different curvature on said shaft, a connecting link, a slide in the connecting link connected to the stitching mechanism, two connecting rods positively reciprocated by said pairs of cams, each end of said connecting link being attached to one of said connecting rods, and means on the driving shaft for automatically varying the position of the connecting link so that its move-

ments depend more on the one or the other connecting rod.

In testimony that I claim the foregoing as my invention, I have signed my name in presence of two subscribing witnesses.

KARL KELLER.
